UNITED STATES PATENT OFFICE.

ALBERT A. PAGE, OF EAST HAVEN, CONNECTICUT, ASSIGNOR TO SARGENT & COMPANY, OF NEW HAVEN, CONNECTICUT, A CORPORATION OF CONNECTICUT.

LOCK.

1,137,786.

Specification of Letters Patent.

Patented May 4, 1915.

Application filed October 19, 1914. Serial No. 867,391.

To all whom it may concern:

Be it known that I, ALBERT A. PAGE, a citizen of the United States, residing in the town of East Haven, county of New Haven, and State of Connecticut, have invented certain new and useful Improvements in Locks, of which the following is a full, clear, and exact description.

This invention relates to locks, and more particularly to extensible cylinder locks, which are adjustable for application to doors of different thicknesses.

The primary object of the invention is the production of an extensible cylinder lock having improved means for connecting the key plug with the bit or rollback in all positions of the latter, whereby the device as a whole is simplified and improved from a manufacturing standpoint, as well as the standpoint of application or use, and the cost of production lowered.

Another object of the invention is to provide a cylinder lock which combines a maximum range of adjustment with the use of comparatively few parts.

To these and other ends, the invention consists in the novel features and combinations of parts to be hereinafter described and claimed.

In the accompanying drawing, Figure 1 is a side elevation of a cylinder lock embodying my improvements, showing the same in the shortest adjustment; Fig. 2 is a similar view from the opposite side of the lock, showing a somewhat longer adjustment; Fig. 3 is a rear end elevation of the lock; Fig. 4 is a section on line 4-4 of Fig. 3; Fig. 5 is a section on line 5-5 of Fig. 2; Fig. 6 is a detail perspective view of a portion of the key plug and the extension or coupling member integral therewith; Fig. 7 is a fragmentary section on line 7-7 of Fig. 2, and Fig. 8 is a view similar to Fig. 7, showing a somewhat modified construction.

My improved cylinder lock comprises a main part or cylinder lock proper 10 and an extension 11 adjustably connected therewith. The main part 10 is, for the most part, of usual construction, having a case 12, a face plate or escutcheon 13, a pin tumbler extension 14, a key plug 15, a retaining washer 16 for the key plug, and the usual pin tumblers (not shown). In the embodiment illustrated, the cylinder extension 11

comprises a disk 17, having exterior screw threads 18, and provided at its rear end with a rotatably mounted bit or rollback 19 of the usual form. At one side of the main part 10 is a lug 20 engaged by an adjusting screw 21. The head 22 of the adjusting screw 21 is rotatably mounted in the disk 17 of the cylinder extension 11, as shown in Fig. 7, and is provided with a nick 23 for a screw driver, so that by turning the screw 21 in one direction or the other, the lock proper and the extension may be brought together, as shown in Fig. 1, or separated, as shown in Fig. 2. On the other side of the main part 10 is a lug 24, which is engaged by a smooth guide pin 25 rigid with the extension 11. A suitable stop 26 at the free end of guide pin 25 may be used for preventing the main part of the lock and the extension from becoming completely disengaged from each other.

In accordance with my invention, the operative connection of the key plug 15 with the rollback 19 is effected in substantially the following manner: The key plug 80 is provided at its rear end with an integral extension 27 adapted to telescope with a part carrying the rollback 19. The extension 27 may be readily formed on the key plug in the process of manufacturing the latter. 85 The extension 27 is of polygonal cross-section, and moreover it extends around the keyway 28, as shown in Fig. 6. By preference, the part 27 will be rectangular in cross-section, and it will inclose the keyway 90 at the top and sides but not at the bottom. The rear extremity of the part 27 extends into a correspondingly formed aperture 29 in a collar 30 rotatably mounted in the extension 11. The collar 30 is round and fits 95 snugly in a round hole 31 of the disk 17, being provided at the front end with a shoulder 32 fitting a counter-bore in the disk so as to prevent rearward displacement of the collar relative to the extension. At the 100 rear of the collar 30, the same has applied thereto the bit or rollback 19, which may be secured to the collar by means such as the screws 33. The rollback 19 is provided with a recess 34 in line with the recess 29 (Fig. 5), 105 so that in the shortest adjustment of the cylinder lock the extension on the key plug may extend completely through the collar and the opening in the rollback, as shown more particularly in Fig. 4. The washer 16 110

for retaining the key plug in the lock proper is secured to the rear end of the key plug by screws 35 located on opposite sides of the extension 27. The washer is, of course, provided with an opening which fits around and conforms to the extension on the key plug. The collar 30 is provided at its upper part with a tenon 36 projecting rearwardly from the disk 17, and fitting the upper portion of the opening 34 in the rollback 19, whereby the mounting of the rollback on the cylinder extension is strengthened.

Fig. 1 shows the position of the parts in the shortest adjustment of the cylinder lock and Fig. 2 shows a longer adjustment. The member 27 which telescopes the supporting collar or member of the rollback 19 engages said member non-rotatively so that the rotary movement of the key plug will be effectively transmitted to the rollback in all the various positions to which the cylinder extension 11 may be adjusted. One of the main advantages resulting from my invention lies in the fact that while the part 27 serves permanently as an effective coupling member between the key plug and the rollback, as stated, it does not in any way interfere with the key, inasmuch as it extends around the keyway, or, in other words, is provided with a portion of the keyway. Hence a lock is produced in which the case 12 may be considerably shorter than the shank of the key. Therefore it will be apparent that the invention provides a cylinder lock which may be very short in the adjustment of minimum length, while the adjustment to maximum length depends only on the length of the coupling member.

In Fig. 8, I have shown a modified arrangement of adjusting screw 21^a. In this case, the head 21^b of the screw is fixed in the cylinder extension, and the threaded shank of the same passes with a certain amount of clearance through an opening 20^a in a lug 20^b on the main part of the lock. Lock nuts

22^a and 22^b threaded on the screw at opposite sides of the lug 20^b are adapted to contact with the respective faces of said lug. The adjustment of the cylinder extension may be obtained in an obvious manner by releasing one of the lock nuts and tightening up the other.

Without limiting myself to the construction shown, I claim:

1. In an extensible cylinder lock, a coupling member of substantially rectangular cross-section formed integral with and projecting rearwardly from the key plug, said coupling member inclosing the keyway at the top and at the sides, and a cylinder extension having a rollback connected with said coupling member; substantially as described.

2. In an extensible cylinder lock, the combination with the main part of the lock, of a coupling member integral with the key plug, and presenting upright walls on opposite sides of the keyway, and between which walls the key may be inserted, and a cylinder extension having a rollback connected with said coupling member; substantially as described.

3. In an extensible cylinder lock, the combination with the main part of the lock, of a coupling member integral with and projecting rearwardly from the key plug, said member presenting an extension of the keyway and having walls inclosing the keyway at the top and at the sides, a retaining washer for the key plug surrounding and conforming to said coupling member, and a cylinder extension having a rollback carrier telescoping said coupling member; substantially as described.

In witness whereof, I have hereunto set my hand on the 16th day of October, 1914.

ALBERT A. PAGE.
